UNITED STATES PATENT OFFICE.

FRANK X. WILD, OF AMHERST, WISCONSIN.

CLOSET.

1,419,839.

Specification of Letters Patent. Patented June 13, 1922.

Application filed March 21, 1921. Serial No. 454,123.

To all whom it may concern:

Be it known that I, FRANK X. WILD, a citizen of the United States, residing at Amherst, in the county of Portage and State 5 of Wisconsin, have invented new and useful Improvements in Closets, of which the following is a specification.

This invention relates to improvements in chemical closets, the principal object of the 10 invention being to provide means for facilitating the emptying thereof.

Another object of the invention is to provide valve means for controlling the outlet of the closet with means for actuating said 15 valve means.

This invention also consists in certain other features of construction and in the combination and arrangement of the several parts, to be hereinafter fully described, illustrated 20 in the accompanying drawings and specifically pointed out in the appended claim.

In describing my invention in detail, reference will be had to the accompanying drawings wherein like characters denote like or 25 corresponding parts throughout the several views, and in which:—

Figure 1 is a sectional view of the invention.

Figure 2 is a top plan view with the cover 30 removed.

Figure 3 is an enlarged sectional detail view.

In these views 1 indicates the container which is provided with an outlet 2 in its 35 bottom which is connected with a drain 3. The bottom of the container slopes to the outlet as shown at 4. A valve 5 is adapted to close the outlet, said valve consisting of a plate which is hingedly connected with the 40 bottom, as at 6, and is adapted to engage a

seat 7 suitably formed to provide a tight joint when the valve is closed. The valve stem 8 is formed of two parts connected together by a spring 8' and the upper part of this stem is connected with a hook 9 by a 45 turn buckle 10. The hook 9 is provided with a handle 9'. This hook engages the top of the container and is so adjusted by the turn buckle as to place tension upon the spring 8' so as to hold the parts with the valve 5 in 50 closed position when the hook is engaging the top of the container.

From the above it will be seen that the container can be easily and quickly emptied by removing the hook from the upper edge 55 of the container and permitting the valve to swing downwardly to open the outlet so that the contents can pass into the drain.

It is thought from the foregoing description that the advantages and novel features 60 of my invention will be readily apparent.

I desire it to be understood that I may make changes in the combination and in the combination and arrangement of the several parts, provided that such changes fall within 65 the scope of the appended claim.

What I claim is:—

A device of the class described comprising a container, an outlet at its lower end, a drain connected with said outlet, a downwardly opening valve plate hinged to the bottom of the container, a two-part rod swiveled at one end to the valve plate, a spring connecting the two parts together, a turn buckle attached to the rod and a hooked 70 member connected with the turn buckle and adapted to engage the upper edge of the container.

In testimony whereof I affix my signature.

FRANK X. WILD.
